UNITED STATES PATENT OFFICE

EVERETT WORTHINGTON, OF CHICAGO, ILLINOIS, ASSIGNOR TO THE HAMMOND CLOCK COMPANY, OF CHICAGO, ILLINOIS, A CORPORATION OF DELAWARE

DESIGN FOR A CLOCK CASE

Application filed June 29, 1931. Serial No. 40,366. Term of patent 14 years.

To all whom it may concern:

Be it known that I, EVERETT WORTHINGTON, a citizen of the United States, residing at Chicago, in the county of Cook and State of Illinois, have invented a new, original, and ornamental Design for a Clock Case, of which the following is a specification, reference being had to the accompanying drawing, forming a part thereof.

The figure is a front perspective view of a clock case showing my new design.

I claim:

The ornamental design for a clock case, as shown.

In witness whereof, I hereunto subscribe my name this 24th day of June, 1931.

EVERETT WORTHINGTON.
